(57) **CLAIM**

The ornamental design for the weighted body suit, as shown and described.

DESCRIPTION

FIG. 1 is a front perspective view of a weighted body suit showing my new design;

FIG. 2 is a front view of the weighted body suit of FIG. 1.

FIG. 3 is a rear view of the weighted body suit of FIG. 1.

FIG. 4 is a right side view of the weighted body suit of FIG. 1.

FIG. 5 is a left side view of the weighted body suit of FIG. 1.

FIG. 6 is a top view of the weighted body suit of FIG. 1; and,

FIG. 7 is a bottom view of the weighted body suit of FIG. 1.

The broken lines are included for the purpose of illustrating environmental structure and form no part of the claimed design.
